Howson & Howson

UNITED STATES PATENT OFFICE.

HARRY F. WANAMAKER, OF PHILADELPHIA, PENNSYLVANIA, ASSIGNOR TO PROC-
TOR & SCHWARTZ, INCORPORATED, OF PHILADELPHIA, PENNSYLVANIA, A COR-
PORATION OF PENNSYLVANIA.

TOP-STRIPPING MECHANISM FOR HOSEIERY DRIERS.

Application filed August 13, 1928. Serial No. 299,403.

This invention relates to means for removing stockings from forms, and constitutes an improvement on the device shown and described in a prior U. S. Patent No. 1,126,619, 5 issued to Harry Coulston and Walter M. Schwartz, under date of January 26, 1915.

As shown and described in the said prior patent, a series of stocking forms are movably mounted in spaced relation on a suitable 10 frame embodied in a suitable drying apparatus. In passing through the drying apparatus the stocking forms assume a substantially vertical position and as each stocking form emerges from the drying apparatus it assumes 15 a substantially horizontal position, the toe and heel portions of the form, with a stocking thereon, entering between jaws or fingers of a gripping device, which, as the stocking form continues to be moved along the drier 20 frame, holds the stocking tightly, whereupon the form is withdrawn from the stocking.

The top portion of the stocking being stretched over the larger or broader part of the stocking form clings closely to this portion of the form, and thereby presents a certain resistance to the removal of the stocking from the form, and this resistance, in the case of the modern sheer stockings, has a tendency to stretch the stocking and to cause the stocking fabric to break or separate at one place or another, due to the pull on the stocking being applied at one end and the greater resistance being applied at or adjacent the opposite end. 30

In order to prevent this stretching or tearing of the stocking, I have devised a means 35 for assisting in the removal of the stocking from the form, which is adapted to apply its energy at or adjacent the place where the greater resistance prevails.

40 Referring to the drawings:

Fig. 1 is a plan view of sufficient of the machine shown in the said prior patent to permit the illustration of my invention as applied thereto;

45 Fig. 2 is a front elevation of the mechanism shown in Fig. 1;

Figs. 3 and 4 are respectively a plan and front elevation of one detail of the invention;

50 Figs. 5 and 6 are respectively a plan and front elevation of another detail of the invention; and

Fig. 7 is a perspective view of a detail shown in Figs. 3 and 4.

As shown in Fig. 1, A illustrates a portion

of the frame of the drier. B illustrates one 55 of the stocking forms of the series running through the drier after having assumed its horizontal position for the removal of the stocking C therefrom. D illustrates the means which grips and holds the stocking 60 while the form is moved along the frame A in the direction of the arrow *x*, the fingers *d*, *d* actually gripping the toe and heel portions respectively. E illustrates the table on which the stocking falls when removed from the 65 form B and released by the fingers *d*, *d*.

Each of the stocking forms B is carried by a suitable mechanism *b* having a portion or shank *b*¹ which rides in a suitable slot *a* in the frame A.

70 The means for moving the forms B along the frame A and other operating parts of the drier have not been shown, being clearly illustrated in the above mentioned prior patent and forming no part of the present invention.

75 The present invention comprises a suitable pad 1 having a suitably roughened or friction surface 2 which is adapted to engage the stocking C on the form B adjacent the top *c*¹ of the stocking, which, as shown, is applied 80 to the wider portion of the form B.

In the present instance, I have shown the pad 1 as comprising a stiff bristle brush which performs the requisite function, i. e. starting the stocking off the form, quite efficiently. 85 Obviously, any form of friction pad, such as rubber, carding cloth, etc., may be utilized without departing from the essential features of the invention.

The starting pad 1 is secured to one end of 90 an arm 3, the opposite end of which is pivotally attached, as at 4, to one end of an operating lever 5, see Figs. 3, 4 and 7.

The lever 5 is pivotally mounted intermediate its opposite ends on a stud 6 which is secured to the frame A. The end 7 of the lever 95 5, opposite that to which the arm 3 is attached, projects across the slot *a* in the frame A, into the path of the shanks *b*¹ of the carriers *b* of the forms *b*.

100 Intermediate its opposite ends the arm 3 passes between vertically extending walls 8, 8 of a suitable bracket 9 forming part of a guiding and elevating mechanism 10, said bracket being secured to the frame A by 105 means of screws 11, 11.

On the under side of the arm 3 is a shoe or projection 12 having a shoulder 12^a formed

therein which is adapted to co-operate with a notched or fish tail end 13 of an elevating latch 14, which is pivoted at 15 to the bracket 9, underneath the arm 3, see Figs. 5 and 6.

5 The latch 14 is adapted to swing about the pivot 15 into various angular positions within limits prescribed by stops 16 and 17 carried by the bracket 9.

In operation, when one form B is laid in its 10 horizontal position the next preceding form has been moved and is moving along the frame A at a point adjacent the lever 5, whereupon the shank b^1 of the said preceding form carrier b strikes the lever 5 and turning 15 it upon its pivot 6 moves the arm 3 longitudinally.

Longitudinal movement of the arm 3 while in its full line position, as shown in Fig. 6, causes the shoulder 12^a on the said arm to abut 20 the fish tail end 13 of the latch 14. Continued longitudinal movement of the arm 3 causes the said latch 14 to turn upon its pivot until the latch engages the stop 17 on the bracket 9, which elevates the arm 3 into its broken line 25 position as shown in Fig. 6.

Elevation of the arm 3 as described causes the starting pad 1 to be brought into engagement with the stocking carried by the horizontally disposed form B, and thereafter 30 causes a relative movement of the starting pad 1, in a direction toward the foot of the stocking, with respect to the said form. This relative movement between the pad 1 and the form B starts the removal of the stocking 35 from the form and thereby relieves the resistance above referred to.

As the arm 3 approaches the extreme limit of its longitudinal movement in the direction toward the foot of the stocking the point 13^a 40 of the fishtail end 13 of the latch 14 strikes the under side of the projection or shoe 12 on the arm 3 and acts as a fulcrum on which the arm 3 pivots to release the point 13^b from behind the shoulder 12^a, which permits the latch 14 45 and the arm 3 to drop, thereby removing the pad 1 from contact with the stocking C in the form B.

As the form B moves in the direction of the arrow α , the stocking C is removed from the 50 form B in the manner described in the above mentioned prior patent.

After the shank b^1 of the preceding form B passes the lever 5, a spring 20, having one of its ends secured to the lever 5 and its opposite end secured to the frame A, moves the arm 3 in an opposite longitudinal direction, 55 until the shoulder 12^a is again in front of the point 13^b of the latch 14, whereby the device is reset for a repeat of the cycle when another 60 form is presented for stripping.

If for any reason it should be advisable to discontinue the operation of the starting pad 1 the same may be held in an inoperative position by a hook 25 pivoted at 26 to the arm 3 65 and adapted to engage the end of the lever 5,

as shown in Fig. 7. When the hook 25 is in this position the spring 20 will not function to return the elements to the starting point of the cycle as described above.

When the hook 25 is in its inoperative position as shown in Figs. 3 and 4, a pin 27 protruding from the side of the arm 3 limits the backward movement of the said hook so that it will not interfere with the normal operation of the device. 75

I claim:

1. In a device for stripping stockings from forms comprising means for gripping the stocking and means for effecting relative movement between the form and the stocking so gripping means, the combination therewith of means adapted to engage the stocking and to move the top portion thereof toward the foot portion thereof and relative to the stocking form. 85

2. In a device for stripping stockings from forms comprising means for gripping the stocking and means for effecting relative movement between the form and the stocking gripping means, the combination therewith of a starting pad, means for moving the starting pad into engagement with the stocking adjacent the top of said stocking, and means for moving said pad in a direction toward the foot of said stocking and relative to the stocking form to start the stripping operation. 90

3. In a device for stripping stockings from forms comprising means for gripping the stocking and means for effecting relative movement between the form and the stocking gripping means, the combination therewith of a starting pad, an arm on which said pad is secured, means for moving said arm longitudinally, and means for engaging said arm during its longitudinal movement and thereby moving said arm in a direction at an angle with respect to the said longitudinal movement thereof whereby said pad is caused to engage the stocking and move the top portion thereof toward the foot portion of the same and relative to the form for starting the stripping operation. 100

4. In a device for stripping stockings from forms comprising means for gripping the stocking and means for effecting relative movement between the form and the stocking gripping means, the combination therewith of a starting pad, an arm on which said pad is secured, means for moving said arm longitudinally, a latch adapted to engage said arm during its longitudinal movement to deflect said arm into a path disposed at an angle to the said longitudinal movement thereof, whereby said pad will engage the stocking 115 and move the top portion thereof toward the foot portion thereof and relative to the stocking form for starting the stripping operation. 120

5. In a device for stripping stockings from 130

forms comprising means for gripping the stocking and means for effecting relative movement between the form and the stocking gripping means, the combination there-
5 with of a starting pad, an arm on which said pad is secured, means for moving said arm longitudinally, a latch adapted to engage said arm during its longitudinal movement to deflect said arm into a path disposed at an
10 angle to the said longitudinal movement thereof, whereby said pad will engage the stocking and move the top portion thereof toward the foot portion thereof and relative to the stocking form for starting the stripping operation, means for releasing the deflecting latch from engagement with the said arm, means for re-
15 turning the arm and the pad to their normal positions for the start of another cycle of operations, and means for restraining the said returning means from operation to cause said pad to remain in an inoperative position. 65
9. In a device for stripping stockings from

6. In a device for stripping stockings from forms comprising means for gripping the stocking and means for effecting relative movement between the form and the stocking gripping means, the combination therewith of a starting pad, an arm on which said pad is secured, means for moving said arm longitudinally, a latch adapted to engage said arm during its longitudinal movement to deflect said arm into a path disposed at an angle to the said longitudinal movement thereof, whereby said pad will engage the stocking and move the top portion thereof toward the foot portion thereof and relative to the stocking form for starting the stripping operation, means for releasing the deflecting latch from engagement with the said arm, and means for returning the arm and the pad to their normal positions for the start of another cycle of operations.

40 7. In a device for stripping stockings from forms comprising means for gripping the stocking and means for effecting relative movement between the form and the stocking gripping means, the combination therewith of a starting pad, an arm on which said pad is secured, means for moving said arm longitudinally, a latch adapted to engage said arm during its longitudinal movement to deflect said arm into a path disposed at an angle to the said longitudinal movement thereof, whereby said pad will engage the stocking and move the top portion thereof toward the foot portion thereof and relative to the stocking form for starting the stripping operation, means for releasing the deflecting latch from engagement with the said arm, means for returning the arm and the pad to their normal positions for the start of another cycle of operations, and means for guiding the arm through its cycle of operations.

45 105

50 110

55 115

120

from forms comprising a frame, means for moving a series of forms along said frame in spaced relation, and means for successively gripping the stockings carried by the respective forms, the combination therewith of a starting pad, an arm on which said pad is secured, a lever pivoted to said frame and to said arm and adapted to be engaged by one of said forms in transit, whereby said arm receives a longitudinal movement, a projection on said arm, a latch pivoted to said frame and adapted to engage said projection, whereby said arm is deflected and said pad is caused to engage the stocking carried by another of said forms, continued movement of said arm causing said pad to move the top portion of the stocking carried by the engaged form toward the foot portion thereof and relative to said form for starting the stripping operation, and means for releasing said deflecting latch from said projection to

60 8. In a device for stripping stockings from forms comprising means for gripping the stocking and means for effecting relative movement between the form and the stocking gripping means, the combination therewith of a starting pad, an arm on which said pad

remove the pad from contact with the stocking.

125 11. In a device for stripping stockings from forms comprising a frame, means for moving a series of forms along said frame in spaced relation, and means for successively

gripping the stockings carried by the respective forms, the combination therewith of a starting pad, an arm on which said pad is secured, a lever pivoted to said frame and to 5 said arm and adapted to be engaged by one of said forms in transit, whereby said arm receives a longitudinal movement, a projection on said arm, a latch pivoted to said frame and adapted to engage said projection, where- 10 by said arm is deflected and said pad is caused to engage the stocking carried by another of said forms, continued movement of said arm causing said pad to move the top portion of the stocking carried by the engaged form 15 toward the foot portion thereof and relative to said form for starting the stripping operation, means for releasing said deflecting latch from said projection to remove the pad from contact with the stocking, and a spring ex- 20 tending between said lever and said frame for returning the said arm and the pad carried thereby to their normal positions.

12. In a device for stripping stockings from forms comprising a frame, means for 25 moving a series of forms along said frame in spaced relation, and means for successively gripping the stockings carried by the respective forms, the combination therewith of a starting pad, an arm on which said pad is secured, a lever pivoted to said frame and to 30 said arm and adapted to be engaged by one of said forms in transit, whereby said arm receives a longitudinal movement, a projection on said arm, a latch pivoted to said frame 35 and adapted to engage said projection, whereby said arm is deflected and said pad is caused to engage the stocking carried by another of said forms, continued movement of said arm causing said pad to move the top portion of the stocking carried by the engaged form 40 toward the foot portion thereof and relative to said form for starting the stripping operation, means for releasing said deflecting latch from said projection to remove the pad 45 from contact with the stocking, a spring extending between said lever and said frame for returning the said arm and the pad carried thereby to their normal positions, and a bracket secured to said frame and engaging 50 said arm for guiding the arm through its cycle of operations.

13. In a device for stripping stockings from forms comprising a frame, means for moving a series of forms along said frame in 55 spaced relation, and means for successively gripping the stockings carried by the respective forms, the combination therewith of a starting pad, an arm on which said pad is secured, a lever pivoted to said frame and to 60 said arm and adapted to be engaged by one of said forms in transit, whereby said arm receives a longitudinal movement, a projection on said arm, a latch pivoted to said frame and having a notched end into which 65 said projection is adapted to enter, con-

tinued longitudinal movement of said arm causing said latch to turn on its pivot and thereby deflect said arm in its movement, said pad being thereby caused to engage the stocking carried by one of the forms and to move the top portion of the stocking toward the foot portion thereof and relative to the form, further movement of said arm causing the point at one side of the said notch in the latch to engage the under side of the 70 arm and thereby release the second point of said notch from said projection, permitting the arm, the pad and the latch to assume their normal positions.

14. In a device for stripping stockings 80 from forms comprising a frame, means for moving a series of forms along said frame in spaced relation, and means for successively gripping the stockings carried by the respective forms, the combination therewith of a starting pad, an arm on which said pad is secured, a lever pivoted to said frame and to said arm and adapted to be engaged by one of said forms in transit, whereby said arm receives a longitudinal movement, a projection on said arm, a latch pivoted to said frame and having a notched end into which 85 said projection is adapted to enter, continued longitudinal movement of said arm causing said latch to turn on its pivot and thereby deflect said arm in its movement, said pad being thereby caused to engage the stocking carried by one of the forms and to move the top portion of the stocking toward the foot portion thereof and relative to the 90 form, further movement of said arm causing the point at one side of the said notch in the latch to engage the under side of the arm and thereby release the second point of said notch from said projection, permitting the arm, the pad and the latch to assume their normal positions, and a spring for moving said arm in an opposite direction to bring said projection in front of said notch for a 95 repeat of the cycle of operations.

15. In a device for stripping stockings from forms comprising a frame, means for moving a series of forms along said frame in spaced relation, and means for successively gripping the stockings carried by the respective forms, the combination therewith of a starting pad, an arm on which said pad is secured, a lever pivoted to said frame and to said arm and adapted to be engaged by one of said forms in transit, whereby said arm receives a longitudinal movement, a projection on said arm, a latch pivoted to said frame and having a notched end into which 100 said projection is adapted to enter, continued longitudinal movement of said arm causing said latch to turn on its pivot and thereby deflect said arm in its movement, said pad being thereby caused to engage the stocking carried by one of the forms and to move the top portion of the stocking toward the 105 foot portion thereof and relative to the form, further movement of said arm causing the point at one side of the said notch in the latch to engage the under side of the arm and thereby release the second point of said notch from said projection, permitting the arm, the pad and the latch to assume their normal positions, and a spring for moving said arm in an opposite direction to bring said projection in front of said notch for a 110 repeat of the cycle of operations.

16. In a device for stripping stockings from forms comprising a frame, means for moving a series of forms along said frame in spaced relation, and means for successively gripping the stockings carried by the respective forms, the combination therewith of a starting pad, an arm on which said pad is secured, a lever pivoted to said frame and to 115 said arm and adapted to be engaged by one of said forms in transit, whereby said arm receives a longitudinal movement, a projection on said arm, a latch pivoted to said frame and having a notched end into which said projection is adapted to enter, continued longitudinal movement of said arm causing said latch to turn on its pivot and thereby deflect said arm in its movement, said pad being thereby caused to engage the stocking carried by one of the forms and to move the top portion of the stocking toward the 120 foot portion thereof and relative to the form, further movement of said arm causing the point at one side of the said notch in the latch to engage the under side of the arm and thereby release the second point of said notch from said projection, permitting the arm, the pad and the latch to assume their normal positions, and a spring for moving said arm in an opposite direction to bring said projection in front of said notch for a 125 repeat of the cycle of operations.

foot portion thereof and relative to the form, further movement of said arm causing the point at one side of the said notch in the latch to engage the under side of the arm and there-
5 by release the second point of said notch from said projection, permitting the arm, the pad and the latch to assume their normal posi-

tions, a spring for moving said arm in an opposite direction to bring said projection in front of said notch for a repeat of the cycle 10 of operations, and a hook pivoted on said arm and adapted to engage said lever for restraining said spring against operation.

HARRY F. WANAMAKER.
